UNITED STATES PATENT OFFICE.

SAMUEL W. PARR, OF URBANA, ILLINOIS.

CALORIMETER.

1,136,360.

Specification of Letters Patent. Patented Apr. 20, 1915.

Application filed May 6, 1914. Serial No. 836,625.

To all whom it may concern:

Be it known that I, SAMUEL W. PARR, a citizen of the United States, residing at Urbana, county of Champaign, State of Illinois, have invented certain new and useful Improvements in Calorimeters; and I do hereby declare the following to be a full, clear, and exact description of the invention, such as will enable others skilled in the art 10 to which it appertains to make and use the same.

The present invention relates to calorimeters and more particularly to apparatus for use in determining the calorific value of coal 15 and similar combustibles.

It is the object of the present invention to provide an apparatus in which the combustible charge is permitted to attain a high temperature throughout until the combustion 20 is substantially complete, but with means for quickly absorbing the heat thus developed.

More particularly, it is the object of the present invention to protect the combustion chamber from contact with the water or other cooling liquid in which it is immersed until after the combustion is well under way or even is complete, and thereafter to bring 25 the combustion chamber directly in contact with the cooling liquid to effect quick transference of its heat and that of the combustion products which it holds.

The apparatus of my invention possesses various structural features of importance, 30 the objects and advantages of which will be made clear by the following detailed description, which is to be taken in conjunction with the accompanying drawings, wherein—

Figure 1 is a sectional elevation through the containers showing the calorimeter in side elevation; Fig. 2 is a partial side elevation of the container illustrating the spring contact member at its top; Fig. 3 is a section 40 through the calorimeter portions of the driving pulley being broken away; Fig. 4 is a sectional plan on the line 4—4 of Fig. 3; Fig. 5 is a section on the line 5—5 of Fig. 3; and Fig. 6 is an enlarged detail of the 45 electrical contact at the base of the fluid holding vessel.

In the embodiment illustrated, the apparatus comprises an outer container 1 and an inner container 2 spaced apart to form a 50 dead-air space 3 and secured together as by means of a screw 4 with cork spacing wash-

ers 5. These containers may be of insuated fiber, or other material of low heat conducting capacity, and are provided with a double air insulated cover comprising disks 60 6 and 7 held together by screws 8 and spaced apart by washers of cork, felt or the like. Within the inner container and spaced therefrom by supporting blocks 9 is a vessel 10 containing water, or other suitable cooling 65 liquid, wherein the calorimeter may be immersed when combustion of its charge is to be effected. This vessel 10 is preferably of metal and is fitted with a tubular deflector 11 cut away at its bottom to form fluid 70 passages 12 through which circulation of the water may be effected. Supported in this deflector is a cross-bar 13 having arms 14 contacting with the walls of the vessel 10 and serving to center the deflector in the 75 vessel. At the center of bar 13 is a pivot whereon the calorimeter may rest and may be rotated.

At the side of the outer container 1 is a pair of electrical terminals 15, one of which 80 is connected through a copper strip 16 with the contact device shown in detail in Fig. 6 as comprising a tubular socket 17 threaded to receive a nut 18 whereby the copper strip 16 may be held in place, and containing a 85 spring pressed plunger 19 adapted to bear yieldingly against the bottom of the metal vessel 10 to establish electrical connection therewith. The other terminal 15 is connected with a plate 20 secured to container 90 1 and pivotally supporting a spring-arm 21 bearing a thumb-piece 22, and shaped so that it can be pushed down into contact with the top of the rotating element of the calorimeter to establish the flow of current there- 95 through for purposes hereinafter set forth. A thermometer 23 passes through the covers and has its bulb positioned in the annular space between vessel 10 and deflector 11 at about the level of the calorimeter. 100

The calorimeter itself comprises a seamless metal cup 24, preferably of nickel-iron alloy of about the composition 70 per cent. iron and 30 per cent. nickel. In operating the calorimeter by the peroxid method, hereinafter disclosed, a highly corrosive alkaline fusion is formed in the cup, and any corrosive action which it may have on the cup not only shortens the life of the latter, but also introduces an element of error in 110 the heat readings. I have found that a nickel-iron alloy of the composition above

stated is much more resistant than pure nickel or most of the metallic elements, and is well suited for use in the construction of this part of the calorimeter. The chamber walls are of uniform thickness throughout, except at the upper edge, where they are shaped to form a shoulder 25 and an outwardly extending flange 26, the upper face of which is smooth and level to receive a gasket 27. Inclosing the combustion chamber is a cylindrical metal casing, the upper edge of which has an annular recess 28 to receive flange 26, and the extreme upper edge of which is in the form of an annular tongue overlapping the edge of flange 26 and lying flush with the top face thereof and in intimate contact with gasket 27, which serves, therefore, not only to seal the combustion chamber, but also to seal the joint between the combustion chamber and its inclosing casing.

The combustion chamber is provided with a cover 29, preferably of the same nickel-iron alloy, this cover having its central portion shaped to enter the combustion chamber with a snug fit and for a distance far enough to protect gasket 27 from the vapors and products of combustion developed in the chamber. With this arrangement, gasket 27 may be of rubber, and this I have found to be a great convenience. The gasket lies in an annular recess in cover 29 and the extreme outer edge of the latter is in the form of an annular lip 30 which overlaps the upwardly extending tongue of the casing, thereby protecting the rubber gasket from squeezing out laterally, and in other ways contributing to the security of the joints.

Cover 29 carries an integral, tubular stem 31, the lower portion of which is provided with a tapered hole to receive an insulating gasket 32 of rubber, or the like, wherein is fitted a tapered socket 33 threaded to a conducting rod 34, which passes upward through stem 31 and is attached by means of a nut 35 to a hub 36 whereon a driving pulley 37 may be mounted for rotating the calorimeter in its bath when desired. The nut 35 is of conical outline and cooperates with the spring contact arm 21, as shown in Fig. 2. An insulating bushing 38 of rubber, or the like, is interposed between the pulley and the main portion of the stem, not only to electrically insulate the two parts, but also to prevent the escape of heat upward through the stem to the pulley. When the apparatus is in use, bushing 38 lies at about the level of the container tops and keeps substantially all of the heat within in the containers, where it can be measured.

As a means for igniting the combustible charge in the combustion chamber, I make use of a fuse-wire 39, one end of which is connected to a terminal 40 screwed directly

into cover 29, and the other end of which is connected through a similar terminal 41, the shank of which is screwed into sleeve 33, and holds an insulating disk 42 over the conical opening in cover 29.

Each of the terminals has a hole and an inclined slot opened at its upper or outer end to form a notch, and in mounting the fuse-wire on the terminals, its end is pushed through the hole for about 1/4 of an inch and then bent sharply down against the face of the terminal. The remainder of the wire is then wound two or three times around the terminal at the narrow part formed by the slot binding in the short end passed through the eyelet, and finally the wire is bent downward in line with the terminal to form a loop from the other terminal similarly strung up. With this arrangement there is certainty of electrical contact between the fuse-wire and the terminals, and the construction is rugged and well adapted to withstand the high temperatures and corrosive conditions present in this type of apparatus. Preferably, the terminal blocks are made of the above mentioned nickel-iron alloy.

The upper portion of the casing is screw-threaded to receive a cap 43, which overlaps the top of cover 29 and serves to hold it tightly in position with its gasket 27 under compression. The outer face of this screw cap may be of octagonal outline, as shown in Fig. 5, to serve as a wrench seat, whereby the cap may be screwed into place. The central portion 44 of the casing is similarly provided with an octagonal wrench seat, whereby it may be held while the cap is being screwed into position. Mounted on the lower portion of the casing is a spring-band 45 carrying paddles 46, so that when the apparatus is rotated, a circulation of the cooling water will be effected.

The casing which incloses combustion chamber 24 is spaced therefrom to form an annular air chamber about 1/64 of an inch across and extending throughout substantially the entire length of the combustion chamber. The bottom of the casing is provided with a flange 47 above which is a metal bottom 48 which may be called a floating bottom, in the sense that it may move upward until its central pedestal 49 contacts with the bottom of the combustion chamber. Pedestal 49 has a height of from 1/32 to 3/32 of an inch, so that when thus in contact it leaves an additional air space below the bottom of the combustion chamber. Very small holes 50 are drilled through the side of the casing to communicate with the air space which envelops the combustion chamber, but these holes are so small and are so positioned, that they do not allow water to flow in and make contact with the combustion-cup when the apparatus is sub-

merged preparatory to ignition of the charge. At the center of the floating bottom 48 is a socket 51 for receiving the pivot of cross-bar 13 (Fig. 1) whereon the entire 5 apparatus turns when pulley 37 is driven from a suitable motor, not shown.

The combustible charge to be used in this apparatus may consist of 1/2 grm. of coal ground to 60 or 100 mesh, 1 grm. of potassium chlorate, $KClO_3$, and, approximately, 10 grms. of sodium peroxid of standard strength. The coal and potassium chlorate are weighed carefully and the sodium peroxid is measured. When the mixture is in 15 the combustion chamber, and tightly sealed up with the fuse-wire in place, the apparatus may be shaken to effect thorough mixture of the charge, and the calorimeter may then be lowered into the water until the floating bottom 20 strikes the pivot and is forced up into contact with the bottom of the calorimeter. At this stage of the operation, the combustion chamber is enveloped substantially throughout in a protective layer of air lying 25 in the narrow space between the casing and the combustion chamber.

After rotating the apparatus until the temperature conditions have become constant, a suitable voltage may be applied to 30 terminals 15 and the spring contact arm 21 may be forced down into contact with terminal 35, thereby passing current through the fuse-wire and through the calorimeter to the pivot-bar 13, from which it passes 35 down by way of the spring-pressed contact 19 and finally to the other terminal 15. The momentary flow of current will burn the fuse and ignite the charge, and the reaction will go on in accordance with the principles and 40 method set forth at length in my Patent No. 673,325, issued April 30, 1901. During the initial stages of the reaction and while the temperature of the combustion chamber is going up, the air immediately surrounding 45 the combustion chamber will be expanded and forced out through the small holes 50, and under these conditions there is no chilling of the charge through contact with the walls of the container, and substantially 50 complete ignition and combustion results; but as soon as the charge begins to cool, the contraction of the air permits the entry of water, and this is drawn into contact with the combustion chamber and finally rises 55 almost to the top of the annular air space between the casing and the combustion chamber. By thus bringing the water into intimate contact with the combustion chamber, as soon as the combustion is substantially 60 complete, a quick transference of the heat is effected, and there is no need to wait for its slow transference through a dead air space or upward to the top of the combustion chamber, where it is in contact with the 65 other metal parts. The heat transference is

substantially complete at the end of four or five minutes, whereas if the heat were compelled to pass across the air space, or, by conduction, up through the points of contact at the upper edge of the cup, the time required 70 would amount to from ten to twenty minutes, and this would permit errors inadmissible in practice.

While the combustion is going on, the apparatus is steadily rotated by means of its 75 pulley and circulates the water, or other cooling liquid, through the openings 12 in shield 11 and upward around the calorimeter, so that it may pass down again between the deflector and the vessel to complete the 80 circulation. After the thermal determinations are complete, and the calorimeter has been removed from the water, its screw-cap is turned off with a wrench and the cover lifted out, after which the floating bottom 85 48 can be forced up to lift the calorimeter out of its casing for further treatment of the residue. This enables the operator to take hold of the outside of the cup and not contaminate the residue of the charge by putting his fingers on the inside of the cup where they would be brought in contact with the condensed alkali vapors produced incidental to the foregoing process. After removal of the combustion chamber, the bottom 90 48 may be taken out entirely and the entire apparatus may be thoroughly wiped out and dried, and made ready for further use.

I claim:

1. In a calorimeter, the combination of a 100 combustion chamber, means for igniting a charge therein, a perforate envelop shielding said combustion chamber from the cooling fluid until combustion is well under way and thereafter permitting direct contact of 105 the cooling fluid with the combustion chamber to effect rapid transference of the heat; substantially as described.

2. In a calorimeter adapted for immersion in a cooling liquid, the combination of 110 a closed combustion chamber wherein a charge may be ignited, and an envelop with an air chamber protecting said combustion chamber from direct contact with the liquid until after combustion is substantially complete said envelop having an opening for the admission of cooling liquid.

3. In a calorimeter adapted for immersion in a cooling liquid, a closed combustion chamber in which a charge may be ignited, 120 and a casing enveloping said combustion chamber with a limited air space intervening, said casing having openings which permit the expanding air to escape, said casing protecting said combustion chamber from direct contact with the cooling liquid until after the temperature of the combustion chamber begins to decrease.

4. In a calorimeter adapted for immersion in a cooling liquid, the combination of a 130

- closed combustion chamber wherein a charge may be ignited, a casing enveloping said combustion chamber with an air space intervening, and said casing having holes through which the heated air may escape while the temperature of the combustion chamber is increasing and through which water may be drawn in when the temperature of the combustion chamber begins to decrease, thereby producing quick transference of the heat of the burning charge to the cooling liquid in which the calorimeter is immersed.
5. In a calorimeter adapted for immersion in a cooling liquid, the combination of a closed combustion chamber wherein a charge may be ignited, a casing enveloping said combustion chamber with an intervening air gap, said casing having a floating bottom limiting the air space below the combustion chamber when the apparatus is mounted in position for ignition of the charge.
6. In a calorimeter adapted for immersion in a cooling liquid, the combination of a combustion chamber wherein a charge may be ignited, and a casing enveloping said combustion chamber with an intervening air gap, said casing having a removable bottom and having holes through which heated air may escape while the combustion chamber is increasing in temperature, and through which water may enter into direct contact with the combustion chamber when the temperature thereof is decreasing.
7. In a calorimeter, the combination of a combustion chamber, a casing secured thereto and spaced from the body of the combustion chamber by a narrow air gap, a cover fitting down into said combustion chamber and having a recess, a rubber gasket in said recess serving as a gas-tight closure for said combustion chamber and for said air gap, and a collar overlapping said cover and threaded to said casing, whereby the gasket may be held tightly to its seats.
8. In a calorimeter, the combination of a combustion chamber, a cover fitting down within said combustion chamber and having an annular recess, a rubber gasket in said recess seated on the upper edge of said combustion chamber, and a casing enveloping said combustion chamber and spaced therefrom to form an air gap, the upper edge of said casing contacting with said rubber gasket and means for holding in place said cover and its gasket.
9. In a calorimeter, the combination of a combustion chamber, means for sealing said combustion chamber with a rubber gasket while protecting the rubber from direct contact with the heated products of combustion, a casing inclosing said combustion chamber and spaced therefrom to form an enveloping air chamber, said chamber being sealed by said rubber gasket, and said casing having air openings through which hot air may escape while the combustion chamber is increasing in temperature, and through which water may be admitted subsequently to quickly cool said combustion chamber.
10. In a calorimeter, the combination of a combustion chamber, having at its top an outstanding flange, a casing spaced from said combustion chamber and having its upper edge flush with the upper edge of the combustion chamber, a gasket seated on said upper edges and a cover for said combustion chamber having a recess for said gasket, said cover extending into the combustion chamber far enough to protect said gasket from the hot products of combustion.
11. In a calorimeter, the combination of a combustion chamber, having at its top a shoulder and an outstanding flange, a cylindrical casing fitting against said shoulder and having a recess receiving said flange, a cover fitted to said combustion chamber and provided with a rubber gasket protected by a part of said cover from direct contact with the products of combustion within the chamber, and a cap overlapping said cover and threaded to said casing, said cap and casing having wrench seats and said casing having air openings; substantially as described.
12. In a calorimeter, the combination of a combustion chamber, a casing inclosing said combustion chamber but spaced therefrom to form an air gap, a cover fitting down within said combustion chamber and having an annular recess, a rubber gasket in said recess lying against the upper edge of said combustion chamber and against the upper edge of said casing, and a cap overlapping the top of the cover and in threaded engagement with said casing to hold the cover in place.
13. In a calorimeter, the combination of a combustion chamber, a cover therefor, a gasket between said cover and said chamber, a casing inclosing said combustion chamber and spaced therefrom to form an enveloping air chamber, said casing having openings through which heated air may be expelled as said combustion chamber heats up, and through which a cooling fluid may be drawn when the combustion chamber begins to cool, and a cap threaded to said casing and holding the cover of said combustion chamber in place.
14. In a calorimeter for use in the combustion of coal in the presence of a peroxid, a closed combustion chamber and means for igniting a charge therein, said combustion chamber consisting essentially of 70 per cent. iron and 30 per cent. nickel; substantially as described.
15. In a calorimeter for the oxidation of coal by sodium peroxid, a closed combustion chamber and means for igniting a charge

therein, the exposed metal within said combustion chamber being an alloy of about 70 parts iron and 30 parts nickel.

16. In a calorimeter adapted for immersion in a cooling fluid, the combination of a combustion chamber, a cover therefor, means for holding said cover in place, said cover having a stem whereby the calorimeter may be rotated in a cooling liquid, a driving pulley supported by said stem and a heat insulating bushing in said stem below said driving pulley.

17. In a calorimeter adapted for immersion in a cooling liquid, the combination of a combustion chamber, a cover therefor having a hollow stem, an electrical conductor passing through said stem for ignition of the charge within the combustion chamber, a pulley mounted on said stem whereby said calorimeter may be rotated in a cooling liquid, and heat insulating means between said pulley and said combustion chamber to limit the conduction of heat through said stem to said pulley.

18. In a calorimeter adapted for rotation in a cooling fluid, and having an upright stem, the combination of a pulley mounted on said stem and whereby said calorimeter may be rotated, and a heat insulating bushing between said pulley and the main portion of said stem.

19. In a calorimeter, the combination of a metal vessel for holding liquid, a tubular deflector therein having fluid openings near its base, a supporting pivot carried by said deflector, a calorimeter mounted to turn on said pivot and having paddles for establishing a circulation of cooling liquid throughout said deflector, there being an electrical connection to the body of said calorimeter through said deflector and vessel, and means for conveying current to the inside of said calorimeter for ignition of a fuse-wire electrically connected with the body of said calorimeter.

20. In a calorimetric apparatus, the com-

bination of an insulating container, a fluid supporting vessel within said container, a calorimeter mounted to rotate in said vessel and having fuse-supporting terminals, one 50 connected with the body of the calorimeter and the other insulated therefrom, means for establishing connection with the body of the calorimeter, and a conducting spring arm supported by said container and movable to 55 establish an igniting circuit within said calorimeter while the latter is rotating.

21. In a calorimetric apparatus, the combination of a calorimeter having an upright stem with a conductor therein exposed at 60 its top, a sealed insulating container enveloping said calorimeter and a yielding contact arm supported by said container and movable into contact with said conductor to initiate a flow of current in said conductor; 65 substantially as described.

22. In a calorimeter, the combination of a closed combustion chamber wherein a charge may be ignited, a pair of terminals therein, one electrically connected with said 70 combustion chamber and the other insulated therefrom, each of said terminals having an eye and having an inclined slot open at its upper end, and a fuse-wire wrapped entirely around said terminals at the slots and having its ends passed through the eyes and bound under said wrappings.

23. In a calorimeter, the combination of a combustion chamber, a cover therefor, and a terminal threaded into said cover and having an eye through which the end of a fuse-wire may be passed, said terminal also having an open notch at which the fuse-wire may be wrapped entirely around the terminal to insure good electrical connection; 80 substantially as described.

In testimony whereof I affix my signature, in presence of two witnesses.
